UNITED STATES PATENT OFFICE.

RALPH E. NOBLE AND LOUIS E. MITCHELL, OF CHICAGO, ILLINOIS, ASSIGNORS TO MORGAN-GARDNER ELECTRIC COMPANY, OF CHICAGO, ILLINOIS.

BUFFER AND DRAW-GEAR.

1,094,375.

Specification of Letters Patent. Patented Apr. 21, 1914.

Application filed December 30, 1912. Serial No. 739,178.

To all whom it may concern:

Be it known that we, RALPH E. NOBLE and LOUIS E. MITCHELL, citizens of the United States, residing at Chicago, in 5 the county of Cook and State of Illinois, have invented certain new and useful Improvements in Buffers and Draw-Gears, of which the following is a specification.

This invention relates more particularly 10 to the draw-gear or coupling devices of cars or locomotives and is especially applicable to mining locomotives, although not limited to such use.

In accordance with our invention we prefer to construct the draw-gear so that it will also serve as a buffer.

The objects of this invention are; to provide a draw-gear or coupling device which will occupy comparatively small space; to 20 provide such a gear or coupling device which may be attached to the draw beam or end of the locomotive frame without having to extend inwardly past the end of the frame; to 25 provide a draw-gear or coupling apparatus in combination with a buffer; to provide a draw-gear or coupling apparatus and buffer which is adapted to accommodate or co-act with the coupling and buffering devices of 30 various forms of cars; and in general to provide such advantages and desirable features as will appear from the following description.

In the accompanying drawings illustrating 35 our invention, Figure 1 is a plan view of a locomotive shown diagrammatically with our improved buffer connected with a car; Fig. 2 is an enlarged plan view of the buffer and draw-gear with parts broken away to show the interior construction; Fig. 40 3 is a front view of the buffer and draw-gear; and, Fig. 4 is a vertical sectional view of the same.

As indicated in these drawings, 5 represents a locomotive having an end beam or channel 6 to which the draw-gear is attached, such construction being intended to represent any suitable locomotive frame. Plates 7, 7, are securely fastened to the beam 50 or channel 6 by means of rivets, or in any

other desired manner. These plates are each provided with two forwardly extending bearings or projections 8. Levers 9 are pivotally mounted on pins or shafts 10 passing through holes in the bearings 8. The outer 55 ends of these levers are pivoted as indicated at 11 to the outer ends of a somewhat peculiarly formed casting or member 12. This casting is provided at its outward ends with rearwardly projecting ears or lugs 13 for 60 receiving the pivot pins 11, such lugs being arranged above and below the ends of the levers 9, in order to form substantial hinges. The casting or buffer member 12 is preferably 65 convex or curved on its face as clearly shown in Fig. 2 and preferably extends approximately across the width of the locomotive frame, although the proportions may be varied for different conditions. This buffer member is somewhat of a channel form, 70 with a top plate 14 which preferably extends back over the top of the channel or beam 6, and with a lower plate 15. The inner ends of the levers 9 each engage with two compression springs, one extending forwardly and the other rearwardly. In order 75 to effect a simple and substantial connection, the levers are provided with lugs or projections 16 which engage with springs 17 fitting in sockets or holes 18 in the plates 80 7 and resting against the face of the channel 6. The levers are also provided with lugs or projections 19 which engage with springs 20 having their opposite ends fitting in sockets or recesses 21 in the buffer 85 member 12.

The buffer member 12 is provided at the center with one or more slots or openings 22 for receiving the coupling links 23. These slots or openings are formed by vertical 90 walls 24 which extend between the plates 14 and 15, and horizontal cross walls 25. The side walls 24 are made sufficiently diverging toward the front of the buffer so as to allow the necessary lateral swinging 95 of the links 23 when the train is passing around curves. The openings 22 are made sufficiently deep so that the links may be pressed or pushed inwardly when the locomotive is pushing a car or when they bump. 100

together. The coupling pin 26 is inserted through holes 27 through the plates 14, 15 and 25. The vertical series of holes 22 permit the links 23 to be adjusted for different heights of coal cars or other cars, which are found to vary greatly in the arrangement of their coupling devices.

From the above description and the accompanying drawings it will be seen that 10 when the locomotive 5 is pulling a car, such as the car 28 in Fig. 1, the pull of the link 23 on the buffer member 12 is transmitted to the car through the yielding arrangement of the levers 9 and springs 17. The forward 15 pull on the pins 11 tends to swing the levers so that their inner ends press against the springs 17, the holes for the pins 10 and 11 being made sufficiently large so as to allow for the necessary relative longitudinal movement 20 between the levers and buffer 12. The pull is therefore divided between the two sides, and by properly proportioning the levers, a very resilient action is obtained without placing too great strain or pressure 25 on the springs. The double hinging arrangement also permits the combined buffer and draw-gear member 12 to swing more or less when the train is passing around a curve. This will prevent undue bending or 30 lateral strain on the draw-gear.

When the device is acting as a buffer the inward pressure on the casting or buffer member 12 tends to press the inner ends of the levers 9 against the springs 20, thereby providing a 35 resilient or yielding buffer action which is divided between a plurality of springs, and the arrangement is such that the apparatus may be designed so as to give the springs such proportional advantage or amount of 40 pressure as may be desired. In various forms of cars, and in particular in coal cars, the buffers are arranged in a variety of ways without any special standards. For instance, there may be a single buffer at the 45 center of the car, or there may be two buffers arranged at various distances from the center dependent upon the particular make. Our improved buffer with the long convex face and substantial width is designed to 50 accommodate a large number, if not all of such various forms of car buffers. The comparatively short longitudinal space required for our device, which for convenience has been designated as a combined buffer and 55 draw-gear, is an exceedingly desirable feature, and this is also true of the arrangement which permits its being fitted to the end of the locomotive frame without having parts projecting inwardly.

60 As the various elements or parts may be readily modified to meet different conditions, we do not wish to limit ourselves to the exact construction herein shown except

as specified in the following claims, in which we claim:

1. A combined buffer and draw-head for cars having a convex face approximately as long as the width of the car, for engagement with various types of buffers, a plurality of vertically arranged pivotal supports for said buffer and draw-head about which it is adapted to rock, and resilient means for holding said buffer and draw-head in normal position with respect to the pivotal supports. 65

2. The combination with a car or locomotive, of a plurality of vertically arranged pivotal supports, a combined buffer and draw-head having a relatively long convex face sufficiently wide to accommodate buffers of different heights and positions on car fronts, and yielding connections between said buffer and said supports for holding the buffer against pulling and pushing strains, but permitting the buffer to rock 85 with respect to said supports. 80

3. The combination with a car or locomotive, of a combined draw-head and buffer having a convex face substantially as long as the width of the cars with which it is to engage, a plurality of vertically arranged pivotal supports, and rocking and yielding connections between said draw-head and buffer and said supports. 90

4. A draw-gear comprising a plurality of 95 oppositely disposed levers pivotally connected with a car or locomotive, a draw-head pivoted to said levers, and springs interposed between the levers and the locomotive for resisting the pulling strain on the draw head. 10

5. The combination with a car or locomotive of brackets arranged at the end thereof, horizontal levers disposed on opposite sides of the center and pivoted to said brackets, 10 a draw-head having its ends pivoted to the outer ends of said levers, and springs interposed between the inner ends of the levers and the locomotive, and other springs interposed between the inner ends of said levers 11 and the draw-head. 11

6. A draw-gear comprising a pair of oppositely arranged plates having brackets thereon and having sockets for receiving springs, levers pivoted to said brackets, a 11 draw-head having its ends pivoted to the outer ends of said levers and having sockets arranged opposite to the inner ends of said levers, springs between the inner ends of said levers and the plates, and between the 12 inner ends of said levers and the draw-head fitting in said sockets, and means for engagement with a coupling link or the like. 12

7. The combination with the frame of a locomotive, of a pair of plates secured to 12 the end at either side of the center thereof,

bearings on said plates and sockets in said plates for receiving springs, a pair of horizontally arranged levers pivoted in said bearings, a convex draw-head having its ends pivoted to said levers, and having sockets for receiving springs, springs interposed between the inner ends of said levers and the plates, and springs interposed between the

inner ends of said levers and the draw-head, and one or more central apertures for receiving coupling links or the like.
